UNITED STATES PATENT OFFICE.

WILLIAM W. DOOLITTLE, OF CHICAGO, ILLINOIS, ASSIGNOR TO CRANE COMPANY, OF CHICAGO, ILLINOIS, A CORPORATION OF ILLINOIS.

TAPER-FINISHING MACHINE.

1,223,571.

Specification of Letters Patent. Patented Apr. 24, 1917.

Application filed April 24, 1916. Serial No. 93,133.

To all whom it may concern:

Be it known that I, WILLIAM W. DOOLITTLE, a citizen of the United States, residing at Chicago, in the county of Cook and State 5 of Illinois, have invented certain new and useful Improvements in Taper-Finishing Machines, of which the following is a full, clear, and exact specification, reference being had to the accompanying drawings, 10 forming a part hereof.

My invention has reference to improvements in that class of machines wherein metallic cast bodies are subjected to the action of cutting tools for taper finishing cylindrical portions of the same; and it has for its principal objects to provide a machine capable of taper finishing such portions, as for example the taper holes of cock bodies, with a minimum expenditure of 20 power and a reduction in wear and tear upon cutting tools and operating parts.

My invention also contemplates the provision of such a machine wherein a cheaper class of tool may be employed than heretofore used, and with a greater facility in getting under the scale of the casting, that is to say, instead of using the customary taper reaming tools for the purpose of finishing the cored taper hole of the casting to 30 the required finish diameter I provide in the machine a series of relatively cheaper straight drills of gradually decreasing diameters arranged with reference to the work to make cuts through the scale in successive 35 lower horizontal planes leaving a series of superposed steps of the stock in such a projecting relation as to be easily ground down to the desired finish diameter by the employment of a suitable reaming tool.

40 My invention further contemplates certain novel details of construction, combination and arrangement of parts of the improved machine, with the purpose of improving the construction, and to increase the 45 efficiency and utility of machines of this character.

These, together with such other objects as may hereinafter appear, or are incident to my invention, I obtain by means of the construction illustrated in preferred form in the accompanying drawings, wherein:—

Figures 1 and 2 represent front and side elevations, respectively of the machine embodying my invention;

Fig. 3 is a vertical sectional view taken 55 through the work table and spindle carrier along the line 3—3 of Fig. 5;

Fig. 4 represents a top plan view of the table and a horizontal section taken through the side frame supports on the line 4—4 of 60 Fig. 1;

Fig. 5 is a similar view taken above the spindle carrier on the line 5—5 of Fig. 1;

Fig. 6 is a side elevation of the table taken at the left of Fig. 1 as indicated therein by 65 the line 6—6;

Figs. 7 and 8 are enlarged detailed views in perspective of certain lever operating mechanism hereinafter referred to; and

Fig. 9 represents an enlarged sectional 70 view of a cock body illustrating the cuts made by the straight drills in the casting.

Referring to the drawings, the numeral 1 indicates the base of the machine, and 2, 3, the hollow side frame standards mounted 75 on the base cross connected by top frame members 45 and a spindle carrier or drill frame 6. Immediately below this drill frame is a work table 7 provided with a guide plunger 8 mounted in a cylindrical 80 standard 9 for relative vertical and rotative movement, the guide plunger having a lesser diameter than the table and depending therefrom into the standard 9 which is secured upon the base 1.

Both the work table and the drill frame are axially in alinement; the latter having formed about its axis a hollow hub 10 whose outer face constitutes a bearing for the combined bevel and spur gear 11, which latter 90 is maintained in relation with the hub by the collar 12 and set screw 13, as in the manner shown in Fig. 3. Meshing with the spur teeth 11^a of the gear 11 are pinions 14 mounted on the upper ends of spindles 15 95 which in turn are carried in bearings 16 formed in the drill frame at points radially of the drill frame axis. Below the bearings are the customary drill couplings or clutches 17 for maintaining the drills A and 100 reamers B in the sockets of their respective spindles.

Mounted on the outer face of the frame standard 3 is a bearing bracket 18 and an inner bearing 18^a for the main shaft 19, 10^b which latter carries the cone pulley 20 and pinions 21 and 22, the cone pulley being connected with any suitable source of power

2
to impart rotative movement to the train of gearing shown. Supported in bearings 23, 23, is a shaft 24 having a gear 51 operatively meshing with the pinion 21 on shaft 19 and 5 a bevel pinion 26 at its inner end engaging the bevel teeth 11^b formed upon the upper face of the gear 11 (Fig. 3). From the description thus far made it will be apparent that the gear 11 in receiving rotative movement from the bevel pinion 26 in turn rotates the spindles and cutting tools through their respective pinions 14.

Vertical openings 27 are formed in the table directly under and in alinement with 15 the cutting tools A, B, and above each of these openings may be rigidly mounted any preferred type of clamp for holding the work in position, one clamp and its cock body only being shown, as indicated respectively by the numerals 28 and 29.

20 The cock body as cast has a taper hole 30 (Fig. 9) slightly less than the required finish diameter, and heretofore it has been customary to finish ream the hole by the employment solely of taper reaming tools, 25 which method involved a large expenditure of power, and furthermore results in excessive wear and tear upon an expensive class of tool, particularly in evidence when initially cutting through the scale of the casting.

30 My invention more particularly resides in providing a group of straight drills A of gradually decreasing diameter, and whose cutting faces as the diameters decrease from 35 the initial drill A¹ to the last drill A⁹ depend from the drill frame in successively lower planes toward the table, so that a cock body will receive successive cuts from successive drills in different planes before the 40 reamers are reached. Nine of these straight drills A and three roughing and finishing reamers B are shown, but any other suitable number may be employed as may be desired 45 for the particular work in hand.

The drill press 6 and work table 7 are relatively movable in vertical and horizontal planes, and in the embodiment shown, the table is the movable member as has already 50 been indicated in describing its relation with the cylindrical standard 9. Means are provided to bring the work up to the tools for the drilling operation comprising a rod 31 extending vertically through the bearing 10, 55 its lower end 31^a being associated with the table and its upper end provided with a yoke 32, the latter having a roller 32^a slidably engaging a lifting cam 33 which is carried by the cam shaft 34. A supplementary 60 raising and lowering means may be advantageously employed in the form of a weight device 35 which in the present instance is located within the hollow standard 2 and connected with the yoke 32 by the flexible connection 25 carried on rollers 36, 36.

The table is in its lowered position when the cam 33 occupies the position taken in Fig. 2, the cam having complementary raising and lowering side faces *a* and *b* and an intermediate face *c* containing the high point of the 70 cam. This face *c* when engaged by the roller 32^a on leaving the lifting face *a* maintains the work operatively in relation with the rotating tools to complete the cuts until the face *b* is reached, whereupon the work is 75 released, the descent of the table being controlled by the weight 35. A locking clutch 49 is secured to the inner face of the standard 2 to lock the table when the latter is 80 raised to its operative position.

85 A ball bearing device 37 (Fig. 3) provides a convenient form of connection between the rod 31 and the table, permitting intermittent rotation of the table so that as each drill finishes its cut in its corresponding cock body the table is lowered and given movement on an arc to bring that particular cock body under the next succeeding and smaller diametered drill, to which it is raised by the 90 table in order to receive an additional cut in a lower plane than the last cut taken. It will be apparent that all of the cock bodies on the table are thus brought successively in a step-by-step or intermittent movement under drills of gradually decreasing diameter 95 which, as already stated, correspondingly depend to have their cutting faces in gradually lowering planes. In other words a cock body inserted on the table at the point *x* is 100 successively subjected to the cutting action of each of the tools until it is released from the last reamer where it is taken out as a finished product, in so far as the purpose of this machine is concerned, and another cock body is thereupon inserted at *x* with the 105 large diametered portion of its taper hole toward the drill frame in readiness to be brought under the first drill A'.

110 Means are also provided for automatically imparting this intermittent revolution to the table, and with this end in view the table is peripherally formed with a series of outwardly projecting lugs 46 spaced apart in relation to the travel of the work from tool to tool in the progression of the table. A 115 flanged ring 44 disposed about the table plunger 8 rests upon the cup seat 9^a formed in the upper terminal portion of the cylindrical standard 9, and is provided with an indexing arm 45 extending outwardly in an 120 horizontal plane toward the table rim. This arm is terminally formed with an upstanding clutch 47 conformed to receive and hold one of the lugs when the table is lowered, and is adapted to impart such movement to the table as to bring that particular lug immediately below the locking clutch 49 and with which it engages when the table is 125 raised to its operative position. As the lug 46 clears the indexing arm clutch 47 the arm 130

is retracted to its first or left hand position in readiness to receive the next succeeding lug as the table is lowered.

For the purpose of imparting this to-and-fro motion to the arm 45, I preferably provide a bell crank lever journaled in the support 50 and whose upper arm 43 is suitably connected with the indexing arm 45 through the interposition of a link 48 capable of slight lateral play (Fig. 7). The numeral 40 indicates a lever mounted in the upper frame member 4, 41 a rod pivotally connecting the outer end of the lever 40 with the lower arm 42 of the bell crank lever, and 37 a table turning or indexing cam 38 mounted on the cam shaft 34 and formed with a way 39 in which the stud 40^a of the lever 40 has movement to rock the bell crank lever and ultimately actuate the indexing arm 45. When the lever stud 40 occupies the position taken in Fig. 2, as more clearly indicated at *r* in Fig. 10, the indexing arm 45 is in its retracted position and starts to turn the table until the point *s* is reached. At this point the arm is in its advanced position and the table stops turning, and in raising releases from the clutch 47 and registers with the lock clutch 49, which serves to maintain the table against rotation when the tools are taking their cuts. During the travel of the stud 40^a between the points *t* and *w* the indexing arm 45 is retracted, and engages the next lug 46 during the movement of the stud between the point *w* and *r* as the table is lowered, a finished cock body being then removed from the machine and another one inserted at the point *x*, which together with the work still on the table are moved under the next adjacent tools. The cam shaft 34 rotates in bearings 52, 52, and receives its rotation through the gears 53, 54, 55 and 56, the latter being mounted on the intermediate shaft 24. Counter-boring drills are also provided to finish face and counterbore the lower face of the cock body, and are carried in bracket bearings 57 mounted on the cylindrical standard 9. Each drill comprises the tool C and its spindle 58, the latter being splined in the sleeve 59 which is flanged over the upper edge of the bearing 57 to form a stop seat 59^a and is provided at its lower end with a pinion 60 abutting the lower edge of the bearing. In this way, the sleeve is held against any vertical movement which might be communicated to it by the spindle in its upward movement toward the work. Rotation is imparted to the sleeves and spindles by the gearing 60, 61, 62, 63, 64 and 65, the latter meshing with the gear 22 on the power shaft 19, (Figs. 1 and 5).

The lower ends of the spindles fit in a double seated casting 66 provided with a bearing 66^a for the pivot pin 67^a which is carried in the outer end of a lifting lever 67.

The latter has connected with it a lifting rod 68 and its inner end is fulcrumed to the base 1 through the interposition of a swinging link 69. (Fig. 8.) Referring to Fig. 1 it will be seen that the upper end of this rod 68 is provided with a yoke 70 having a roller engagement with a lifting cam 71 conforming substantially with the lifting cam 33, and having substantially synchronous rotative movement therewith to lift the counterboring tools to the work.

The initial diameter of the taper hole of the cock body is represented by the dotted line *m*, Fig. 9, and the full line *n* the desired diameter. With the parts positioned and operating as already described, the cock body is first inserted into its clamp at the feed point *x*, and the table automatically turns to bring the body under the first straight drill A' and rises into its locked operative position. This drill thereupon takes the first cut *a'* through the scale of the casting along a vertical line *p* that extends diagonally of the lines *m* and *n* leaving a step *q'* and a shoulder *u*, the depth of the cut *a'* being determined by the conformation of the face *c* of the table lifting cam 33. The cock body, after being lowered, turned, and raised, is then subjected to the cutting action of the succeeding drill A² and the next cut *a²* is made by which the shoulder *u* merges into the second step *q²*, and at the same time another cock body is receiving its first cut from the first drill. Since the cutting face of the second drill is of slightly decreased diameter and depends in a lower plane than that of the first drill, and so on to the last drill A⁹, it will be apparent that the successive cuts when taken leave a series of superposed steps projecting into the hole of the casting. As each cock body leaves the last drill it encounters the reamers B, of which one or more may be used as desired, and the steps are easily and quickly reamed off by them down to the finish diameter *n* 100 since the scale has already been cut through. During this finishing operation, the lower tools C already raised through the registering holes 27 counterbore and face finish the lower face of the bodies which are then taken 115 out of the machine.

Where external cylindrical portions of a casting, such as the taper and outer face of a cock, are desired to be finished, shell or hollow straight drills and shell reamers may 120 be substituted for those illustrated in the present instance.

From the foregoing description the essential features, elements and operation of the machine, together with the advantages thereof will be clearly apparent to those skilled in the art.

I do not intend to restrict myself to the exact details of construction or to the precise arrangement of the various parts, as 130

shown, as it is manifest that variations and modifications may be made in the features of construction and arrangement without departing from the spirit and scope of my invention and improvements. I therefore reserve the right to all such variations and modifications as properly fall within the scope of my invention and the terms of the following claims.

10 Having thus described my invention and illustrated its use, what I claim as new and desire to secure by Letters Patent, is the following:—

15 1. In a machine of the character described, and in combination, a drill frame and a work support located with reference to each other and relatively movable, a plurality of straight drills in said frame of different diameters constructed and arranged for taking successive cuts in the work in differing depths, whereby to leave steps of uncut stock 20 in each of the cuts, and a taper finishing device for reaming the uncut stock to the desired finish diameter.

25 2. In a machine of the character described, and in combination, a drill frame and a work support operatively disposed for relative rotative and reciprocative movement, means for taper finishing tapered cylindrical portions of the work including a series of differently diametered drills rotatively carried in said frame and constructed and arranged with reference to said support for successively taking progressive cuts in relatively 30 differing depths in said cylindrical portions, whereby to leave superposed annular steps of uncut stock projecting beyond the plane of the desired finish diameter, means for simultaneously rotating said drills, means for imparting relative movement to said table, and means for dressing down said steps to the desired finish diameter.

35 3. In a machine of the character described, the combination of a drill frame and a work support located with reference to each other and relatively movable in horizontal and vertical planes, and means for taper finishing tapered cylindrical portions of the work comprising a plurality of straight drills 40 and one or more taper reamers rotatively carried in said drill frame and constructed and arranged respectively with relation to said table and the work for taking successive vertical cuts at different horizontal depths 50 in said tapered cylindrical portions and for reaming the remaining uncut portions of stock to the finish taper diameter.

45 4. In a machine of the character described, the combination of a main frame, a drill frame therein and a movable work support located with reference thereto, a group of drills rotatably carried in said drill frame, and to the cutting action of which the work is successively and simultaneously subjected 60 when positioned on the table, said drills

projecting from the drill frame toward the table and presenting cutting faces of gradually diminishing diameters at differing depths to the work, means on said main frame for holding said support during the cutting action of the drills, and means operatively associated with said work support for retracting the work table and the work from the drills as a cut is taken by the same in said work.

5. In a machine of the character described, and in combination, a drill frame, a group of spindles therein, a work table disposed with reference thereto, said table and frame being relatively movable, and means for successively taking cuts on cylindrical tapered portions of the work, comprising drills in said spindles presenting straight cutting faces of gradually diminishing diameters to the work and in eschelon with reference to 85 said table.

6. In a machine of the character described, the combination of a drill frame, spindles rotatively carried therein, drills in said spindles, a work table provided with a support 90 and formed with a series of locking portions, means for advancing said table to locked operative position and retracting the same from the drills, and means for imparting intermittent rotary movement on successive 95 arcs in a horizontal plane to said table including an indexing member carried on said support, and adapted to successively engage said locking portions whereby to operatively position said table when in unlocked position.

7. In a machine of the character described, the combination of a drill frame, a relatively movable work turntable below said table, means for imparting movement to the table, 105 in a vertical plane toward and from the drill frame, a lock device adapted to be engaged by said table when in raised position, spindles in said frame, gearing for rotating said spindles, means for imparting intermittent turning movement to the table, and drills in said spindles to the cutting action of which the work is successively subjected, said drills presenting cutting faces of relatively different diameters disposed in different horizontal depths, and actuating mechanism for said means, said table being successively lowered from, turned, and raised to locked operative position in the actuation of said mechanism.

8. In combination, a relatively movable drill frame and a work support operatively disposed with reference to each other, a group of drills constructed and arranged in said frame for successively and progressively taking straight cuts on different cylindrical tapered portions of the work, whereby to leave superposed steps of uncut stock projecting from said portions, means for dressing down said steps to the desired 130

BEST AVAILABLE COPY

finish taper diameter of the work, and means for simultaneously rotating said drills.

9. In a machine of the character described, the combination of a frame, a series of rotary drills, a movable work table disposed with reference thereto and adapted to receive the work in a series, a horizontal rotary shaft mounted in said frame independently of the table, means for operatively advancing and retracting said table relatively of the drills, means for imparting intermittent rotary movement to said table, both said means having separate operative 10 connections to the table and including actuating cam devices constructed and arranged on said rotary shaft whereby said table is successively retracted from, turned, and raised to the drills during rotary movement of said shaft.

10. In a machine of the character described, the combination of a work table adapted to receive and hold a series of articles and having peripheral locking portions, a main frame having a fixed integral support for said table and a drill frame, drills for said drill frame, said table being capable of being advanced and retracted on its support with reference to said drills, a locking device on said main frame adapted to lock with one of said locking portions when the table is advanced, and an indexing arm carried by said support and adapted to engage with another of said locking portions when the table is retracted.

11. In a machine of the character described, the combination of a work table adapted to receive and hold a series of articles and having peripheral locking portions, a main frame having a fixed integral support for said table and a drill frame, drills for said drill frame, said table being capable of being advanced and retracted on its support with reference to said drills, a locking device on said main frame adapted to lock with one of said locking portions when the table is advanced, an indexing arm carried by said support and adapted to engage with another of said locking portions when the table is retracted, and actuating means for said indexing arm.

12. In a machine of the character described, the combination of a relatively movable frame and a work support constructed to receive and hold the work in a serial relation, means for progressively taper finishing tapered cylindrical portions of the work comprising a group of straight drilling and taper finishing tools rotatively carried in said frame and constructed and arranged with reference to said table and the work for taking successive cuts in rela-

tively different horizontal depths in said portions and for dressing down the remaining uncut portions of the stock in said portions to the finish taper diameter of the work, and means for simultaneously rotating said tools.

13. In a machine of the character described, the combination of a relatively movable frame and a work support constructed to receive and hold the work in a serial relation, means for progressively taper finishing tapered cylindrical portions of the work comprising a group of straight drilling and taper finishing tools rotatively carried in said frame and constructed and arranged with reference to said table and the work for taking successive cuts in relatively different horizontal depths in said portions and for dressing down the remaining uncut portions of the stock in said portions to the finish taper diameter of the work, means for simultaneously rotating said tools, and a co-operative cutting device for facing the work.

14. The combination of a work table having peripheral locking lugs, a main frame provided with a lug receiving slideway, a support in said frame for the table, the table capable of reciprocation and rotary movement relatively of its support and said slideway adapted to receive one of said lugs upon reciprocation of the table in one direction, and means for imparting intermittent rotary movement to said table comprising an indexing member revolvably carried by said support and formed with a slideway adapted to receive a locking lug upon reciprocation of the table in the opposite direction, and actuating mechanism operatively associated in said frame for actuating said indexing member to bring another of the lugs in position with reference to the first mentioned slideway.

15. In a machine of the class described, the combination of a main frame comprising standards and a support, a drill frame mounted in said frame comprising drills and a gear for rotating said drills, a work table in said support, a main power shaft in said main frame, a countershaft mounted in said standards and provided with means for imparting relative reciprocative movement to the drill frame and said table and for indexing the latter in phase with said movement, and a gearing mechanism operated by said power shaft and constructed and arranged for simultaneously actuating said gear and said countershaft.

In testimony whereof I have hereunto signed my name.

WILLIAM W. DOOLITTLE
